(57) **CLAIM**

The ornamental design for a landscaping block, as shown and described.

DESCRIPTION

FIG. 1 is a front perspective view of an embodiment of a landscaping block according to my new design.

FIG. 2 is a front plan view of the landscaping block of FIG. 1.

FIG. 3 is a back plan view of the landscaping block of FIG. 1.

FIG. 4 is a top plan view of the landscaping block of FIG. 1.

FIG. 5 is a bottom plan view of the landscaping block of FIG. 1.

FIG. 6 is a left side plan view of the landscaping block of FIG. 1.

FIG. 7 is a right side plan view of the landscaping block of FIG. 1.

FIG. 8 is a front perspective view of an embodiment of a landscaping block according to my new design.

FIG. 9 is a front plan view of the landscaping block of FIG. 8.

FIG. 10 is a back plan view of the landscaping block of FIG. 8.

FIG. 11 is a top plan view of the landscaping block of FIG. 8.

FIG. 12 is a bottom plan view of the landscaping block of FIG. 8.

FIG. 13 is a left side plan view of the landscaping block of FIG. 8; and,

FIG. 14 is a right side plan view of the landscaping block of FIG. 8.
